UNITED STATES PATENT OFFICE

FELIX MOREL, OF FAYETAS, PAR RAZAC-SUR-L'ISLE, FRANCE, ASSIGNOR TO ANCIENS
ETABLISSEMENTS R. CORNELY & CIE. (SOCIETE ANONYME), OF PARIS, FRANCE

SEWING MACHINE

Application filed July 20, 1926, Serial No. 123,758, and in France January 14, 1926.

My invention relates to improvements in sewing machines and particularly to machines which are used for embroidering.

One of the objects of the invention is to provide an arrangement for the vertical guiding of the reciprocating pivot piece in order that during the sewing of embroidery and open work, the embroidery thread may more readily follow the design traced upon the 10 fabric.

Other objects of the invention will be obvious to those skilled in the art with reference to the accompanying drawing, in which—

15 Fig. 1 is an assembly view in elevation of my complete device;

Fig. 2 is a horizontal section on an enlarged scale along the line 2—2 of Fig. 1;

Figs. 3 to 6 are detail views of the guiding 20 elements of Figs. 1 and 2;

Fig. 7 is a longitudinal sectional detail taken through Fig. 1 on an enlarged scale; and

Fig. 8 is a section along the line 8—8 of 25 Fig. 7.

Referring to the drawing, a claw foot Q which produces the displacement of the fabric to be sewed or embroidered, is carried by a presser-foot bar A.

30 The mechanism for operating the said bar A will now be described with reference to Figs. 1, 7 and 8.

A lever K is pivoted at O to a sleeve N fixed to a vertically disposed tube B. The 35 upper arm of lever K bears on a cam surface associated with a member L slidably mounted on needle-driving tube B and fastened to a reciprocable support S by means of a collar R carried thereby. Said support is arranged 40 to be given an alternating movement in a vertical direction by any of the means well known in the art which has not been illustrated since it forms no part of the present invention.

45 It will be noted that when the member L descends, the upper arm of the lever K is pushed to the left as shown in Fig. 7. The lower arm of said lever, therefore, will be displaced toward the right. Said lower arm 50 engages in a slot associated with a circular

member F' having a central opening. Said member F' is fixed to the bar A by means of a collar F rigidly attached to said bar. It will thus be seen that displacement of the lower arm of lever K to the right during the descent of the member L will cause the members F, F' and consequently the bar A to be moved to the right.

Movement of the lever K is opposed by a spring so that when the member L ascends the said lever is returned to its original position and in so doing moves the members F, F' and consequently the bar A to the left.

The sleeve N is guided by two of the surfaces in the opening in member F' and permits the vertical oscillating plane of the elements carried by the needle-driving tube B to be orientated in all directions but without affecting the horizontal reciprocating movement of the presser-foot bar. The means 65 for controlling the orientation of the member N at will is so well known in the art that it has not been illustrated since it has no particular bearing on the present invention.

The horizontal movement of the bar A is 75 combined with another movement in such a manner that the point of intersection of the longitudinal axis of the needle-driving tube B and the plane represented by the line 2—2 in Fig. 1 will be displaced vertically and 80 given a reciprocating movement. The vertical movement of this fictitious point is controlled by a bearing D' carried by a rib D which is adapted to be given a vertical reciprocating movement from the main shaft of the 85 machine by any of the well known means in the art and which has not been illustrated.

In devices known in the art, the bearing referred to, receives a cylindrical projection, 90 forming part of a cross-bar and the presser-foot bar corresponding to the bar A, hereinbefore referred to, is pivoted to said cross-bar in such fashion that it can turn about the vertical axis of said cross-bar. Obviously, 95 since the presser-foot bar, during orientation, must operate in a vertical plane other than that represented by the horizontal axis of said cross bar, it is essential that the said cross-bar turn about the said axis. Now since 100

said cross-bar must, at the same time, be guided by the guide-tube corresponding to the needle driving tube B in the drawing, in such a way that its geometrical center will always coincide with the vertical axis of said tube, the cross-bar must be so formed that a certain latitude of movement will be present with respect to said tube.

By way of example, the interior bore of 10 said cross-bar is frequently given the form of a double-cone with acute salient angles. This arrangement produces very satisfactory operation but is subject to the disadvantage that the acute salient angles thus formed 15 wear rapidly which results in the cross-bar becoming no longer guided by the said tube which gives way to lateral displacement of the cross-bar with respect to the tube.

Having thus outlined the usual guiding 20 arrangement used in machines in current use, the guiding arrangement which forms the object of the present invention will now be described. The guiding is no longer produced by the needle-driving tube B, which 25 gave way to the disadvantages above outlined, but by a pair of vertical slots T_1 and T_2 associated with two fixed elements of the machine. In these slots are lodged and adapted to slide the shoes G carried by the 30 heads e' of the bolts E fastening the bar A to the cross-bar C. The bolts E, as shown in Fig. 3, are also provided with smooth cylindrical projections e which engage in corresponding smooth holes in cross-bar C. The 35 shoes G have their outer faces of cylindrical form to permit oscillation about their transverse axes as shown in Figs. 5, and 6. Oscillation about the axis of the bolts E is assured by means of the projections e turning in the 40 corresponding holes of member C. It will thus be noted that the presser-foot Q is rigidly maintained in parallel relation with the fabric which it advances, a condition which is absolutely necessary for producing regularity 45 of stitching.

The slots T_1 and T_2 above mentioned are produced by providing a recess in the head plate P of the machine, which is usually of cast metal, and disposing therein liners H, 50 H' of tempered steel fastened by means of screws V, V' and between which slides one of the shoes G above mentioned. The other shoe G is adapted to slide in a plate M of tempered steel which is fastened to the cap 55 of the head plate P by means of a screw W. It will be noticed that the bore of member C is noticeably larger than the diameter of needle-driving tube B which is solely for giving sufficient freedom to the tube and not for 60 guiding.

Many variations in my apparatus may be made by those skilled in the art without departing from the scope of my invention, since

65 What I claim is:—

1. In a sewing machine having a presser-foot, an operating bar therefor and a needle driving tube, means concentric with said tube for universally supporting said operating bar, said means comprising a pair of trunnions and a third trunnion extending at right angles to said first-mentioned trunnions, and means independent of said tube for guiding said supporting means in a vertical plane perpendicular with said third 75 trunnion.

2. In a sewing machine having a presser-foot, an operating bar therefor and a needle-driving tube, the combination of a supporting plate concentric with said tube, a pair of arms on said bar, a pair of trunnions on said arms pivotally engaging said supporting plate, means for guiding said trunnions in a vertical direction and operating means for pivotally supporting said supporting plate. 85

3. In a sewing machine having a presser-foot, an operating bar therefor and a needle-driving tube, the combination of a supporting plate concentric with said tube, a pair of arms on said bar, a pair of trunnions on said arms pivotally engaging said supporting plate, means for guiding said trunnions in a vertical direction and a third trunnion extending at right angles to said first mentioned trunnions on said supporting plate, 90 and operating means pivotally engaging said third trunnion for supporting said plate.

4. In a sewing machine having a presser-foot, an operating bar therefor and a needle-driving tube, the combination of a supporting plate concentric with said tube, a pair of arms on said bar, a pair of trunnions on said arms pivotally engaging said supporting plate, a pair of shoes mounted on said trunnions, a support for each of said shoes, and 100 a guide slot in each of said supports, adapted to receive said shoes respectively. 105

5. In a sewing machine having a presser-foot, an operating bar therefor and a needle-driving tube, the combination of a supporting plate concentric with said tube, a pair of arms on said bar, a pair of trunnions on said arms pivotally engaging said supporting plate, a pair of shoes mounted on said trunnions, a support for each of said shoes, a 110 guide slot in each of said supports, adapted to receive said shoes respectively, a third trunnion extending at right angles to said first-mentioned trunnions on said supporting plate, means pivotally engaging said third 115 trunnion for supporting said plate, said 120 trunnion having rounded outer surfaces for permitting pivotal movement of said supporting plate about the axis of said third trunnion.

In testimony whereof I have signed this specification.

FELIX MOREL.
